METHOD OF REMOVING TRASH FROM
PAPER PULPING MACHINES

Edwin Cowles, Cayuga, N. Y., assignor to The Cowles Company, Princeton, N. J., a corporation of New Jersey

Original application March 18, 1940, Serial No. 324,684. Divided and this application June 10, 1941, Serial No. 397,356

3 Claims. (Cl. 92—20)

This invention relates to methods and apparatus for treating paper stock, and pertains more particularly to method and apparatus for defibering, refining and otherwise preparing paper stock for use on paper making machines.

This application is a division of Patent No. 2,265,936 issued December 9, 1941 on my copending application Serial No. 324,684, filed March 18, 1940.

In a prior patent, No. 1,883,597 issued October 18, 1932, I described a method of treating paper stock in which the stock is contained in a vat, and is circulated by a pump which withdraws stock from the vat and returns it thereto, the returned stock being discharged into the vat at high velocity through submerged nozzles. The high velocity jets discharged by the nozzles exercise a defibering and refining effect on the stock due to the tearing effect of the high velocity jets moving through the relatively stationary body of stock in the vat.

Subsequently, in a prior patent, No. 2,219,571 issued October 29, 1940, I described a different form of apparatus utilizing the principle of my aforementioned patent. In said patent, however, instead of withdrawing stock from the vat and returning it to the vat through nozzles, I provide a rotary impeller which is submerged in the vat, which said impeller is provided with open grooves so designed as to discharge high velocity jets from the rim of the impeller, which said jets have the same refining and defibering effect as the jets discharged from the nozzles in the aforementioned patent.

Subsequently, in application Serial No. 314,107, I proposed to increase the surface area of the stock which is discharged at high velocity by discharging the same in the form of a relatively thin circular sheet, such as a relatively thin annular disk. In the preferred embodiment illustrated in said application, this is accomplished by mounting a multiplicity of vanes on the surface of an open impeller disk, adjacent the rim thereof, said vanes being relatively low and being closely spaced, so that stock is discharged at high velocity around the entire periphery of the impeller in the form of a relatively thin annular disk. The surface area of the discharged disk of stock is very great and consequently the refining and defibering effect is very rapid and efficient.

The machine disclosed in application Serial No. 314,107 was adapted for batch operation, that is, a batch of untreated material is placed in the machine, the batch is treated, and the treated batch is removed from the machine.

It is an object of the present invention to provide an improved machine adapted for continuous operation.

It is a further object of the present invention to provide a method of removing undesired trash from the material being treated.

Other objects and advantages of the invention will appear hereinafter.

A preferred embodiment of the invention selected for purposes of illustration is shown in the accompanying drawings, in which,

Figure 1 is a vertical sectional view.

Figure 2 is a plan view of a portion of the impeller.

Figure 3 is a side elevation of one of the impeller vanes.

Figure 4 is a section on the line 4—4 of Figure 2.

Figure 5 is a plan view of a portion of the impeller illustrating a modified form.

Figure 6 is a section on the line 5—5 of Figure 5.

Referring to the drawings, a vat or tank 1 is provided, preferably cylindrical in shape. The bottom of the tank is provided with an aperture to receive the impeller hereinafter described, and the sides and bottom of the aperture may be enclosed to provide a sunken chamber 3. The space between said chamber and the cylindrical side wall of the tank may be filled with concrete 4 to provide a sloping surface as illustrated in Figure 1. Such a sloping surface directs the stock discharged from the impeller, as hereinafter explained, upwardly along the side walls of the tank and assists in maintaining circulation in the stock contained in the tank as indicated by arrows in Figure 1. If desired, fixed directional vanes 5 may be embedded in the concrete to direct the stock which is discharged from the impeller in an upward direction and to restrain to some extent the circulation in a horizontal plane.

An impeller, in the form of a disk 10, is mounted in aforesaid aperture in the bottom of the tank so as to be surrounded by the chamber 3, and may be rotated in any suitable manner, as by pulley 11, driven by motor 12, operating through suitable reduction gears (not shown) mounted in the housing 13.

The impeller disk is provided with a multiplicity of impeller vanes 14 mounted adjacent the rim of the disk, said vanes projecting upwardly from the upper surface of the disk. The said vanes may be secured to the disk in any suitable manner, but in the embodiment illustrated, the vanes are secured, as by welding, to a ring 15 which is set into a groove 16 formed in the disk, which said ring is held in place by

screws 17. Thus, the impeller is of the "open" type, being distinguished from "closed" type impellers by the absence of any enclosures, hoods, shrouds, passages or the like which are commonly used to increase the efficiency of impellers employed for pumping or circulating purposes, but which are wholly unsuited for defibering paper stock.

In order to avoid stapling of stock on the vanes 14, the advancing face 18 of each vane is inclined to the surface of the disk and at an angle such that the fibers engaged thereby roll and slide along the face. The angle of inclination should preferably not exceed 30° and is preferably somewhat less, as for example, the angle illustrated in the drawings is approximately 18°.

The height of the vanes above the surface of the disk is small relative to the diameter of the disk, and should not exceed a ratio of 1 to 30. For example, using a disk having a diameter of 5', the height of the vanes should preferably be about 1½", so that the disk of stock discharged from the impeller will be relatively thin.

The impeller should be rotated at a rate sufficient to discharge the stock at the rim of the impeller at a velocity of at least 1000 ft. per minute and in some cases at considerably higher velocities, as for example, between 1,000 and 2,000 ft. per minute, the particular velocity selected in excess of 1000 ft. per minute depending on the toughness of the stock being treated. For purposes of this specification, therefore, the term "high velocity" is defined as comprehending velocities in excess of 1000 ft. per minute, for tests have shown that while some defibering action may be produced at lower velocities, it is not possible to produce completely defibered stock within the limits of practical operation. At lower velocities it has been found that defibering proceeds with reasonable rapidity until the undefibered pieces of stock reach a certain size, after which the rate of defibering is rapidly reduced or defibering action may cease entirely. Even long continued treatment often fails to produce complete defibering. Using high velocities, as defined herein, however, defibering action proceeds rapidly to completion.

It is important to maintain proper circulation of the stock at all times in order that all portions of the stock may be repeatedly subjected to the action of the impeller. The preferred type of circulation is that which is in the nature of a vortex or whirlpool comprising circulation in both horizontal and vertical planes. It has previously been stated that the sloping sections 4 of the bottom of the tank contribute to this result in directing the stock discharged from the impeller upwardly along the sides of the tank, and it has also been pointed out that excessive circulation in the horizontal plane may be restrained by fixed directional vanes 5.

Another contributing feature in this connection is the relative diameters of the impeller and the tank, for it has been found that in order to maintain proper circulation, the diameter of the impeller should be greater than one fourth and less than one half the diameter of the tank.

Still another contributing feature to the maintenance of proper circulation is the supplementary vanes 25 which are also mounted on the upper face of the impeller disk between the vanes 14 and the center of rotation of the impeller. The advancing face 26 of the vanes 25 may be inclined to the face of the disk, as shown, to prevent pieces of stock from stapling thereon. The

said vanes 25 initially accelerate the stock at the center of the impeller and move it toward the vanes 14 which additionally accelerate it and discharge it in disk form as previously described.

5 Since the vanes 25 continually move stock away from the center of the impeller, thus drawing stock down centrally from the top of the tank, they assist greatly in maintaining the vortical circulation which has been found so highly useful 10 in the operation of this apparatus. In continuous operations the consistency of the stock is usually low and the vortical cavity may extend all the way down to the impeller, so that the impeller may be seen from the top of the tank. 15 This vortical circulation causes the undefibered material which is being added continuously, which said material is frequently in pieces of large size which otherwise tend to float on the surface, to be drawn down into the vortex and to be immediately subjected to the defibering action of the impeller.

In order to permit continuous withdrawal of treated material, an outlet conduit 28 is connected to the chamber 3, and means are provided 25 for effectively controlling the flow of material from the main portion of the tank to the chamber 3 in order to prevent the withdrawal of undefibered material and trash. Thus, in the machine illustrated in Figures 2 and 3 a restricted 30 passage 31 is provided between the edge of the plate 32 and the outside rim of the impeller. Since the passage 31 lies immediately beneath the disk of stock which is being discharged at high velocity by the impeller, it is virtually impossible for pieces of undefibered material or pieces of trash to enter the passage, since the velocity of the stock discharged from the impeller is much greater than the velocity of the material being withdrawn. The high velocity disk serves 40 as a barrier, therefore, to sweep aside any pieces of undefibered material or pieces of trash which tend to move toward the passage without, however, preventing withdrawal of completely defibered material which flows out with the water.

45 However, it is advisable that the trailing ends of the impeller vanes extend across the passage 31 as shown in Figure 3, in order to mechanically dislodge any material which may tend to lodge in the passage, and to clear away any fibers which 50 may staple over the edge of plate 32.

In the form of machine illustrated in Figures 4 and 5, the plate 35 extends into close proximity to the rim of the impeller and the passage for the withdrawal of defibered material is provided 55 by a multiplicity of perforations 36 in the plate. In this form the perforations are cleared by a wiper 37 secured to the impeller having a curved edge 38 extending across the plate. The edge 38 runs in close proximity to the surface of the plate 60 and repeatedly clears the perforations of any fibers which may lodge therein. In this form of machine the disk of stock discharged from the impeller, being discharged immediately adjacent the perforated plate and sweeping across said plate at high velocity, in itself tends to clear the 65 screen perforations, and in so doing enhances the defibering action since the discharged disk is directed directly against any accumulation or concentration of fibrous material which may tend to lodge in the perforations due to their restricted size.

In the continuous operation of such machines, particularly in board mills where waste paper is the material to be defibered, it is desirable to 70 provide for the continuous removal of the trash

which is always present in waste paper as supplied to the mill. The trash content of such waste paper is considerable, frequently running as high as 4%. In a machine having a capacity of 200 tons per day, for example, there will be an accumulation of several hundred pounds of useless trash per hour, and unless such trash is removed continuously, frequent shutdowns are necessary. Such trash is of two varieties, heavy materials such as paper clips, tin cans, glass, stones, etc., and lighter materials such as rags, string, rope, etc. For the removal of heavy materials, I provide trash pits 40 located at the periphery of the tank and communicating therewith by means of a chute 41. The bottom of the chute 15 may be provided with an aperture 42 opening into the pit and controlled by a gate 43 which may be operated by any suitable means.

The circulating movement of the material brings the waste material eventually to a position over one of the pits, and the heavy material drops into the pit. The said pits may be dredged out periodically whenever necessary in any suitable manner.

The removal of lighter trash materials is a much more difficult problem, but I have devised a novel and extremely simple method of removal. By careful observation of the operation of the machine, I have discovered that the vertical circulation tends to concentrate such trash near the center of the circulation in the vertical plane, approximately in the area indicated by the reference character T, which said area extends around the tank in annular form. Furthermore, I have discovered that by trailing the end of a rope or rope like member 50, such as barbed wire, for example, in the tank, the lighter trash materials such as rags, string, rope, etc., tend to wind themselves around the trailing end of rope, and in so doing, tend to wrap in other light trash such as pieces of wood, Cellophane, rubber, etc., which in themselves are incapable of winding around the rope end. After an accumulation of such trash has formed, it is possible to withdraw the rope end with the trash clinging thereto. However, I find that by withdrawing the rope end slowly and continuously, the trash will continue to form itself into a rope even after the original rope end has been entirely withdrawn from the tank. This is particularly true if the baling wires customarily used to bind up bales of

waste paper are thrown into the tank with the bales. These wires wind themselves into the rope and provide sufficient tensile strength to prevent the self-forming rope of trash from breaking as withdrawn. If desired a reel 51 may be mounted at the top of the tank as a convenient means of withdrawal.

It will be understood that the invention may be variously modified and embodied within the scope of the subjoined claims.

I claim as my invention:

1. Method of removing trash from a continuously operating waste paper pulping machine which comprises continuously introducing waste paper material including trash containing rags, string, rope and the like, maintaining a vertical circulation of the material being treated, trailing an end of rope-like material in said circulating material below the surface thereof, and withdrawing said rope-like material after an accumulation of trash has been wound thereon.

2. Method of removing trash from a continuously operating waste paper pulping machine which comprises continuously introducing waste paper material including trash containing rags, string, rope and the like, maintaining a vertical circulation of the material being treated, trailing an end of rope-like material in said circulating material below the surface thereof, withdrawing said rope-like material slowly after an accumulation of trash has been wound thereon, and continuing to withdraw the self-forming rope of trash which forms after withdrawal of said end of rope-like material.

3. Method of removing trash from a continuously operating waste paper pulping machine which comprises continuously introducing waste paper material including trash containing rags, string, rope and the like, maintaining a vertical circulation of the material being treated, trailing an end of rope-like material in said circulating material below the surface thereof, introducing strands of wire into said circulating material with said waste paper material, withdrawing said rope-like material slowly after an accumulation of trash and wire has been wound thereon, and continuing to withdraw the self-forming rope of trash and wire which forms after withdrawal of said end of rope-like material.

EDWIN COWLES.
